RANDALL BRACKETT ANDROS, OF PORTLAND, MAINE, ASSIGNOR OF FORTY-FIVE ONE-HUNDREDTHS TO RUEL B. RIDEOUT, OF SOUTH BERWICK, MAINE.

SHEET-MUSIC TURNER.

1,149,885.

Specification of Letters Patent. Patented Aug. 10, 1915.

Application filed March 11, 1915. Serial No. 18,700.

To all whom it may concern:

Be it known that I, RANDALL B. ANDROS, a citizen of the United States, and a resident of Portland, in the county of Cumberland and State of Maine, have made certain new and useful Improvements in Sheet-Music Turners, of which the following is a specification.

My invention is an improvement in sheet music turners and the invention has for its object to provide mechanism of the character specified having means for supporting sheet music and having means for engaging the individual leaves and for turning said leaves in succession from one side to the other, the said means being capable of operation by the musician, and wherein the leaves may be turned from either side.

In the drawings: Figure 1 is a front view 20 of the improved turner, Figs. 2, 3, 4 and 5 are sections on the line 2—2, 3—3, 4—4 and 5—5 respectively of Fig. 1, each looking in the direction of the arrows adjacent to the line, Fig. 6 is a perspective view of one of the 25 leaf turning arms, Fig. 7 is a section on the line 7—7 of Fig. 5, looking in the direction of the arrows adjacent the line, and Fig. 8 is a sectional view of a modified construction.

The present embodiment of the invention 30 comprises a support consisting of a base plate 1, which has its upper surface grooved or concave longitudinally as indicated at 2 to receive the lower edge of the sheet music 35 or folio, and a back support is provided against which the rear face of the sheet or folio rests. This back support, in the present instance, is a frame 3 composed of wire bent into ornamental figures, the several 40 figures being connected as shown by wire wrappings 4. The frame is adjustably connected to the base by means of loops, each loop consisting of a front member 5 which is slidable through a bearing 6 on the rear 45 side edge of the base 1, a rear member 7 which is connected to the frame, and a bottom connecting portion 8, the said portion 8 being U-shaped and having one end connected to the portion 5 and the other to the portion 7. The portion 7 is connected to the frame by bending the said portion around the frame, as shown in Figs. 1, 2 and 3, and the frame may be adjusted vertically with respect to the base by means of the bearings 50 6 before mentioned.

Set screws 9 are threaded through the base from the front to the rear, and the set screws engage the portions 5 of the connecting loops to secure the frame in adjusted position with respect to the base.

A shaft 10 is journaled vertically with respect to the frame and the base, the shaft being at the center of the base and in rear thereof and the shaft is held rigidly in loops 11 formed in the central figure composing the frame 3, and in bearings 12, 13, 14 and 15 connected to the frame, the said bearings being rings of wood or the like connected to the frame in any suitable manner, and all the bearings are in alinement.

An ornamental cap or head 17 is connected with the top of the shaft 10, the cap or head having an opening at one end engaged by the threaded end of the shaft, as shown in Fig. 2. Each of the turning arms 18 has connected with one end thereof a sleeve or hub 19, the sleeve of each arm having a central opening for engaging the shaft 10. At the other end each arm has an angular depending arm 20 to which is rigidly connected a spring operated clamp 21 for engaging a leaf of the sheet music or of the folio. In the present instance three arms 18 are provided and the arms are arranged on the shaft one above the other between the bearings 13 and 14, and they are held in position on the shaft by the said bearings.

A worm or screw 22 is arranged on the shaft between the bearings 14 and the cap 90 17 and the said screw or worm is in the form of a sleeve having a spiral groove, as shown. A nut 23 is mounted on the screw, the nut having an internal rib engaging the groove, the arrangement being such that when the nut is moved downward the screw will be rotated. The nut has oppositely extending arms 24 which have eyes 25 at their end engaging over vertical guides 26 which are a part of the frame 3 before mentioned and the said guides are parallel as shown, being arranged on opposite sides of the shaft 10.

Arms 27 extend upwardly from a collar 28 which is mounted to slide on the shaft 10 above the bearing or stop 12 before mentioned and a coil spring 29 is arranged between the collar and the bearing or stop, the spring normally acting to force the collar upward. Each of the arms 27 is con-

nected rigidly at its lower end to the collar 28, and at its upper end each arm has an eye 30 engaging over the adjacent arm 24.

It will be evident that when the collar 28 is moved downwardly the nut 23 will also be moved downwardly, and the collar is moved downwardly by a link 31, the link being connected rigidly at its upper end to the collar and being connected at its lower end to a finger piece or handle 32 for convenience in moving the link. The link 31 is guided at its lower end by a guide bar 33, connected to the lower end of the shaft 10 and the said lower ends of the shaft and link are bent at an obtuse angle to the body portions thereof, as shown at 10^a and 31^a respectively. The link and the shaft are parallel throughout their course, and each of the turning arms 18 is limited in its swinging movement to approximately an arc of 180° by means of transverse stop and release rods 34 which are arranged behind the shaft 10 and are supported by the frame.

The stop rods 34, three in number in the present instance, are arranged one above the other and normally stand just below the body portion of the adjacent arm. The rods are of spring wire and are attached rigidly at their ends to the frame. Each rod is engaged by an eye 35 connected with an operating link to be later described. The eyes 35 engage the rods near their centers and at their ends the rods are rigidly secured to vertical braces or struts 36 forming a part of the frame 3 before mentioned. A coil spring 37 encircles each rod near one end, and each rod has a head 38 at the said end. The springs are fixed at the end adjacent to the head and from the opposite end of each spring a flexible member 39 extends around the collar or hub 19 of the adjacent arm 18 to a connection with the said arm, as indicated at 40.

It will be noted that each of the sleeves or hubs 19 of the turning arms is peripherally grooved, as shown at 41, to receive the flexible member, and each flexible member passes almost entirely around the hub or collar when the turning arm is at the right of the stand. When the turning arms lie at the right of the music stand, as shown in Fig. 1, the spring 37 is under tension and the said spring tends normally to swing the arm to the left. Each turning arm is normally held at the right of the stand by means of a latch 42 rigidly fastened to the adjacent rod 34, and extending forwardly from the rod into engagement with the turning arm.

Each of the latches, as shown in Fig. 7, has a lug engaging in front of the arm to restrain the action of the spring 37 and it will be evident that until the latch is released the arm cannot be turned. The latches are released in succession by spring-

ing the central portion of the rod which supports the latch downwardly by means of links 43—43^a. Each link consists of a lower section 43, having eyes 44 mounted to slide on the shaft 10, and an upper section 43^a having eyes 44^a also sliding on the shaft. The adjacent eyes of the sections are rigidly connected to constrain the sections to move together when the links are moved downwardly. Each of the sections 43 has angle portions at its ends which carry the eyes 44, and each of the sections 43^a has similar angle portions at its ends which carry the eyes 44^a.

The links are arranged well in rear of the shaft 10 and the frame 3 and the angle portions extend forwardly beyond the links 31 to the sliding connection with the shaft 10. A handle 45 is connected with the lower end of the lower section of each link, each of the handles having an eye rigidly connected to the adjacent eye 44 of the link. By means of the handles, the links may be moved downwardly to release the latches that hold the arms from turning.

The operation of turning the leaves from the right to the left is as follows: All of the turning arms are turned to the right of the stand in succession, and as each arm is turned to the right it is engaged with the adjacent latch to hold the arm from turning to the left under the influence of the spring 37 connected therewith. As the arms are turned, the links 43—43^a are moved downward to set the latches, and after the latches are set the device is ready for operation. When it is desired to turn the first leaf the lowermost handle 45 is pressed downwardly, the handles 45 serving as finger pieces for releasing the turning arms. When the lowermost handle 45 is pressed downward the lowermost turning arm 18 is released from its latch 42 and the spring 37 immediately swings the arm to the left of the stand and the leaf to which the clamp 21 of the arm is connected is also swung to the left. When the music on the second leaf has been played, the intermediate handle 45 is pressed downward releasing the second turning arm and the third arm is released in like manner. All of the turning arms and the leaves connected therewith may be returned to the right of the stand for a repeat of the music if desired. This returning of the arms is brought about by the screw 22 and the nut 23. An angle arm is connected with the screw, the said arm consisting of a portion 46 extending radially from the screw and a portion 47 depending in front of the rod 34, and the turning arms swing over into engagement with this depending portion 47. After all of the turning arms have swung to the left of the stand they may be returned to the right by depressing the finger piece 32 of the link 27—31. When this finger piece or handle is pressed down-

ward the nut 23 is moved longitudinally of the screw 22 and the screw is rotated toward the right of the stand, swinging the angle arm 46-47 and swinging all of the 5 turning arms to the right of the stand. When the arms have been swung to the right the latches 42 are depressed and the music is ready for a repeat.

The improved music leaf turner is of 10 simple construction, and it is also simple in operation. The turning arms are spring controlled and when they are released the spring operates said arms to turn the leaves. The nut 23 is returned to normal position by 15 the spring 29. The links 43-43^a are returned to normal position by the resiliency of the spring arms 34. Since only the central portion of the rods is sprung downward, as soon as pressure on the handle is 20 released, the resiliency of the rod will return the latch to the engaging position. The improved stand is of light weight, and may be arranged on the stand of a piano or on a 25 music stand of any construction. While but three turning arms are shown, it is obvious 30 that there is no limit except convenience to the number of arms that might be operated in the same manner. The arms are not dependent upon each other, and each arm moves independently of all the other arms.

It will be understood that the rods 34 may be secured to the braces 36 in any desired manner. In Fig. 8 is shown a modified construction of spring for operating the 35 turning arms. In this construction the arms 18^a, but one of which is shown, and corresponding to the arms 18 of the construction just described, have hubs 19^a journaled on the shaft 10^a. The upper face of each hub 40 is provided with an axial depression 50, and a coil spring 51 encircles the shaft 10^a at each hub. The lower end of the spring 51 is received in the depression 50 and one end of the spring passes through a radial 45 opening 52 leading from the depression to the periphery of the hub. This end of the spring is secured to the hub in any suitable manner as indicated at 53, while the other end of the spring is secured to the shaft as 50 indicated at 54. The operation is precisely the same, as with the turning arm just described.

I claim:

1. A music leaf turner comprising a base 55 and a stand adjustably connected with the base, a shaft arranged in vertical position at the center of the stand, a series of turning arms journaled on the shaft to swing from side to side of the stand, each arm 60 having a leaf engaging clamp at its outer end, a spring in connection with each arm and normally acting to swing the arm from one side of the stand to the other, a vertically movable latch engaging each arm to 65 prevent the swinging movement thereof

under the influence of the spring, a link connected with each latch, each link being mounted to slide on the shaft and having at its lower end a finger piece for engagement by the operator to move the link to 70 release the latch, a common means for simultaneously returning all of the arms to normal position after they have been swung by the spring, said means comprising a sleeve journaled on the shaft above the arms 75 and having a spiral groove, a nut having lugs for engaging the groove and mounted for longitudinal movement on the sleeve, means connected with the nut and engaging the frame for guiding the nut and for preventing rotation thereof, a link connected with the nut and mounted to slide on the shaft and having a finger piece at its lower end for moving the link vertically to rotate the sleeve, said sleeve having an angle arm 80 extending behind the arms in their swung position, and a spring engaging the link to return the nut to normal position.

2. A music leaf turner comprising a base and a stand adjustably connected with the base, a shaft arranged in vertical position at the center of the stand, a series of turning arms journaled on the shaft to swing from side to side of the stand, each arm having a leaf engaging clamp at its outer 90 end, a spring in connection with each arm and normally acting to swing the arm from one side of the stand to the other, a vertically movable latch engaging each arm to prevent the swinging movement thereof 100 under the influence of the spring, a link connected with each latch, each link being mounted to slide on the shaft and having at its lower end a finger piece for engagement by the operator to move the link to 105 release the latch, a common means for simultaneously returning all of the arms to normal position after they have been swung by the spring, said means comprising a sleeve journaled on the shaft above the arms 110 and having a spiral groove, a nut having lugs for engaging the groove and mounted for longitudinal movement on the sleeve, means connected with the nut and engaging the frame for guiding the nut and for preventing rotation thereof, and a link connected with the nut and mounted to slide on the shaft and having a finger piece at its lower end for moving the link vertically to rotate the sleeve, said sleeve having an angle arm 115 extending behind the arms in their swung position.

3. A music leaf turner comprising a base and a stand adjustably connected with the base, a shaft arranged in vertical position at the center of the stand, a series of turning arms journaled on the shaft to swing from side to side of the stand, each arm having a leaf engaging clamp at its outer 120 end, a spring in connection with each arm 125

and normally acting to swing the arm from one side of the stand to the other, a vertically movable latch engaging each arm to prevent the swinging movement thereof 5 under the influence of the spring, a link connected with each latch, each link being mounted to slide on the shaft and having at its lower end a finger piece for engagement by the operator to move the link to release 10 the latch, and common means for simultaneously returning all of the arms to normal position after they have been swung by the spring, said means having a link slidably mounted on the shaft and provided at its 15 lower end with a finger piece for operating the same.

4. A music leaf turner comprising a base and a stand adjustably connected with the base, a shaft arranged in vertical position 20 at the center of the stand, a series of turning arms journaled on the shaft to swing

from side to side of the stand, each arm having a leaf engaging clamp at its outer end, a spring in connection with each arm and normally acting to swing the arm from one side of the stand to the other, a vertically movable latch engaging each arm to prevent the swinging movement thereof 25 under the influence of the spring, a link connected with each latch, each link being mounted to slide on the shaft and having at its lower end a finger piece for engagement by the operator to move the link to release the latch, and a common means for simultaneously returning all of the arms to normal position after they have been swung by the spring. 30

RANDALL BRACKETT ANDROS.
